(57) CLAIM

The ornamental design for a uniform scrapbook, as shown and described.

DESCRIPTION

FIG. 1 is a perspective view of our ornamental design for a uniform scrapbook.

FIG. 2 is a top plan view of the uniform scrapbook of FIG. 1. FIG. 3 is a bottom plan view of the uniform scrapbook of FIG. 1.

FIG. 4 is a left side elevation view of the uniform scrapbook of FIG. 1.

FIG. 5 is a right side elevation view of the uniform scrapbook of FIG. 1.

FIG. 6 is a rear elevation view of the uniform scrapbook of FIG. 1.

FIG. 7 is a front elevation view of the uniform scrapbook of FIG. 1; and,

FIG. 8 shows a perspective view of the uniform scrapbook of FIG. 1 in an open condition.

The broken line showing of external topstitching in FIGS. 1 and 2 is included for the purpose of showing conventional stitching of the uniform scrapbook and forms no part of the claimed design. The broken line showing of internal elements shown in the figures is for illustrative purposes only and forms no part of the claimed design.
